UNITED STATES PATENT OFFICE.

FRANK KUHN AND JAY A. HAND, OF DETROIT, MICHIGAN, ASSIGNORS TO AMERICAN ELECTRICAL HEATER COMPANY, OF DETROIT, MICHIGAN, A CORPORATION OF MICHIGAN.

COMBINED HANDLE ATTACHMENT AND NAME-PLATE FOR ELECTRICALLY-HEATED INSTRUMENTS.

1,258,122.

Specification of Letters Patent. Patented Mar. 5, 1918.

Application filed January 25, 1917. Serial No. 144,371.

To all whom it may concern:

Be it known that we, FRANK KUHN and JAY A. HAND, both citizens of the United States of America, residing at Detroit, in 5 the county of Wayne and State of Michigan, have invented certain new and useful improvements in Combined Handle Attachments and Name-Plates for Electrically-Heated Instruments, of which the following 10 is a specification, reference being had thereto in the accompanying drawings.

The invention relates to heated tools, such for instance as sad-irons, and has particular reference to the construction of attachment means for the handle, which performs the additional function of a name-plate.

In the drawings:

Figure 1 is a perspective view of a sad-iron embodying the improved construction; 20 Fig. 2 is a central longitudinal section therethrough;

Fig. 3 is a cross-section;

Fig. 4 is a perspective view of the handle-bearing and name-plate. 25 A is the body of a sad-iron or other heated instrument of any suitable construction, and B is the handle therefor. C are bolts or studs projecting upward from the body, which engage the shank D of the handle 30 to secure the same to the body.

To form a firm connection between the handle and the body it is desirable to have a wide supporting bearing, and it is also desirable to limit the amount of heat-conducting contact. With our improved construction instead of directly attaching the handle shanks D to the body A, a seat member E is provided, preferably a sheet-metal stamping. This member as specifically shown is oval-shaped and is provided with a marginal downturned flange F for directly bearing upon the body A, and is recessed at G and H to receive the end portions of the shanks D. The recesses G and 45 H are of a depth preferably substantially equal to the thickness of the shanks, but the flange F is of greater depth. This

will leave a space between the bottom of the recess and the top of the body which is filled by a washer I sleeved upon the stud 50 C. Clamping nuts J are provided for engagement with the studs, which when tightened will firmly clamp the shanks D in the recesses G and H and will also hold the member E upon the body. Thus a firm 55 connection is formed between the body, as the width of the member E will prevent any tendency to rock.

The member E in addition to performing the mechanical function just described 60 is valuable for use as a name-plate. The marking may be placed upon the exposed top portion of the member and may be formed by the same stamping operation which presses the blank. 65

What we claim as our invention is:

1. In a sad iron, the combination with a body portion and a handle therefor having shank portions, of a member formed of pressed sheet-metal having a flat top portion, depressions therein forming seats for the handle shank portions and conforming thereto and a depending marginal portion resting on said body, said member forming a raised boss on the body and constituting 75 a name plate.

2. In a sad-iron, the combination with the body portion and a handle therefor having shanks extending inward from the opposite ends thereof, of a bearing member 80 formed of a pressed sheet-metal blank, having a marginal flange for bearing on the body and recesses for receiving the shanks, and clamping studs passing through said sheet-metal member and shanks and securing the same to said body. 85

In testimony whereof we affix our signatures in presence of two witnesses.

FRANK KUHN.
JAY A. HAND.

Witnesses:

HARRY W. LUYCKX,
ARCHIE OAKES.
